& Bear LLP(57) **CLAIM**

The ornamental design for a tapered box, as shown and described.

DESCRIPTION

FIG. 1 is a front, top, and left perspective view of the tapered box showing my new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a left side elevational view thereof; and,

FIG. 7 is a right side elevational view thereof.

1 Claim, 6 Drawing Sheets---
